BATHING SUIT

Charles Lewis Martin, Winston-Salem, N. C., assignor to Indera Mills Company, Winston-Salem, N. C., a corporation of North Carolina

Application April 28, 1932, Serial No. 608,098

1 Claim. (Cl. 2—67)

This invention relates to improvements in beach or bathing suits and it has for its object the provision of a one-piece garment of the type designated having no back above the waist line, permitting the complete exposure of the back of the wearer to the air and sun for the purpose of acquiring a tan, and at the same time being so constructed that when worn, the front portion is stretched both longitudinally and transversely in the zone of the breasts, functioning as a brassière in supporting the bust.

A more specific object of the invention is the provision of a one-piece bathing suit having the trunk portion belt-supported at the waist, and having the upper part adapted to clothe the front only of the body, terminating laterally in substantially longitudinal under-arm edges extending to the belt line and having shoulder straps extending rearwardly of the arms and a divided cross strap bridging the rear portions of said shoulder straps, the parts of which cross strap are united by a button or other equivalent means and holding the shoulder straps in place, the cross strap being capable when unbuttoned, of being thrown back so as to leave the entire back of the wearer bare and to prevent the marring of the tan by a streak of lighter shade which would otherwise be left beneath the cross strap.

Other objects of the invention will appear as the following description of a preferred and practical embodiment thereof proceeds.

In the drawing which accompanies and forms a part of the following specification, and throughout the several figures of which the same characters of reference have been employed to designate identical parts:

Figure 1 is a perspective view showing the front of the bathing suit;

Figure 2 is a similar view showing the backless feature;

Figure 3 is a cross section taken along the line 3—3 of Figure 4; and

Figure 4 is a rear view of the bathing suit.

Referring now in detail to the several figures, the numeral 1 represents a bathing suit preferably of elastic knit fabric, having the lower part or trunks 2 of usual construction, with belt straps 3 at the waist line and adapted to be supported upon the body by a belt 4.

The upper part of the bathing suit is preferably integral with the trunks and extends only substantially semi-circumferentially about the front of the waist line, terminating laterally in substantially longitudinal edges beneath the

arms, there being no back portion to the bathing suit except in the form of the shoulder straps 5 and 6 and the divided cross strap 7, the parts of which emanate from the shoulder straps overlapping, being held together between the shoulders by a button 8 or other suitable fastening means.

The upper portion or body 9 is characterized by the fact that not only do the arm holes descend to a lower level than the neck opening, but the elasticity of the fabric permits the shoulder straps to draw the fabric rearwardly beneath the arms as at 10, stretching the bathing suit transversely in a zone which overlies the breast, performing the function of a brassière in supporting the bust. The elevated relation of the indentation of the neck to that of the arm holes also provides an uncut front area above the level of the lower edges of the arm holes which through the intermediary of the shoulder straps, distributes the pull of the shoulder straps uniformly along the entire upper edge of the brassière area, reacting against the fabric adjacent the waist line which may be considered fixed and therefore, stretching the brassière area vertically, thus assisting in maintaining it flat.

The shoulder straps can only exercise this stretching function upon the brassière area when they maintain a fixed position upon the shoulders and this fixed position is determined by the provision of the cross strap 7.

The backless nature of this bathing suit renders it particularly advantageous to those desiring to acquire a tan over the entire area of the back above the waist line. Since it is however, objectionable to have the uniformity of this tan marred by the light untanned streak which normally would be formed beneath the cross strap 7, the latter can be unbuttoned and thrown back or tucked beneath the shoulder straps so as to expose an unbroken expanse of the skin to the air or the sun's rays.

While I have in the above description disclosed what I believe to be a preferred and practical embodiment of the invention, it is obvious that those skilled in the art that certain tolerances in the shape and construction of the bathing suit are permissible without departing from the spirit of the invention as claimed.

I claim:—

One-piece elastic bathing suit comprising a trunks portion, belted at the waist line, and a body portion emanating from the front semi-circumference only of the trunks portion, and

terminating laterally substantially at the sides of the body, said body portion being provided with integral shoulder straps extending to the back forming arm holes, a brassière area having its 5 upper boundary defined by a circumferential line joining the bottoms of said arm holes and physically determined when the bathing suit is distended by the body by being the line of demarcation between a laterally stretched area and an 10 area immediately above, not so greatly stretched, the body portion being provided with a neck indentation cut to a higher level than the bottoms

of said arm holes whereby to provide an unbroken area above said brassière area for distributing the longitudinal strain produced when said bathing suit is distended, uniformly along the said line of demarcation, said shoulder straps drawing the 80 underarm parts of the front portion rearwardly, tensioning said brassière area laterally whereby it is maintained taut across the breasts, and a cross strap connecting said shoulder straps at the 85 back, intermediate the tops and bottoms of the arm holes for holding them in place.
